DESIGN FOR A COMBINED HANDLE AND FRAME FOR MIRROR OR SIMILAR ARTI- CLE

Harry S. Berk, Brooklyn, N. Y.

Application June 25, 1938, Serial No. 78,058

Term of patent 7 years

To all whom it may concern:

Be it known that I, Harry S. Berk, a citizen of the United States, residing in the Borough of Brooklyn, county of Kings, city and State of New York, have invented a new, original, and ornamental Design for Combined Handle and Frame for Mirror or Similar Article, of which the following is a specification, reference being had to the accompanying drawing, forming a part thereof, in which:

Fig. 1 is an elevation of a combined handle and frame for a mirror or similar article embodying my new design;

Fig. 2 is a section through the frame taken on line 2—2 of Fig. 1; and

Fig. 3 is a section taken on line 3—3 of Fig. 1.

The opposite side of the combined handle and frame is similar to that shown in Fig. 1.

I claim:

The ornamental design for a combined handle and frame for mirror or similar article, as shown and described.

HARRY S. BERK.
